UNITED STATES PATENT OFFICE.

JAMES A. CRAIG, OF SAULT STE. MARIE, ONTARIO, CANADA.

TRACKED LUMBER DRIER.

Application filed January 17, 1923. Serial No. 613,127.

My present invention relates to an improvement in the method of and apparatus for drying lumber, and has for its object an improvement in extracting moisture from wet or green lumber by mechanical means.

One of the most important objects of my invention is to remove a large quantity of moisture from large amounts of lumber in the shortest space of time in a mechanical manner, and this is accomplished by whirling balanced quantities of lumber at high rotative speeds, whereby centrifugal action, and absorption action of the air removes, within a short period, a high content of moisture from the lumber by reason of the action of the two above noted forces.

By whirling the lumber around a central pivot, the air is forced over the lumber surface in the same manner as from a blower or fan, but the drying process is greatly advanced by the centrifugal force to which the lumber is submitted at the same time, because the water is naturally expelled from the innermost cells of the lumber towards its surface, where it is immediately absorbed and carried away by the rushing air.

My machine is, further, constructed so as to permit its easy loading and unloading with the least possible loss of time, and with perfect security in handling and operation, the machine being located in the center of a track construction leading into a drying room in such a way that the trucks on which the lumber is piled enter, on one side of the room, with wet lumber thence to pass in turn into my apparatus which is then revolved, to be dried, and after this operation, the trucks are taken out of the machine again onto the track to be shifted out at the other end of the room into the adjacent dry room, or drying kiln, heated in the usual manner, in which the drying process is accomplished.

Many other advantages possessed by my apparatus and method of lumber drying over older and present processes will be made apparent in the following specification, but my invention is not limited to these, as many changes may be made in its construction without departing from the spirit of the invention or exceeding the scope of the appended claims.

In the accompanying drawings, Figure 1 is a longitudinal front view of the apparatus.

Fig. 2 is a longitudinal front view of the apparatus, and also showing means for rotating the cages and brake means for stopping the apparatus.

Fig. 3 is a cross-sectional view on line 3—3 of Fig. 2, and

Fig. 4 is an enlarged view of the lumber compressing mechanism of the apparatus, to hold the lumber in position during the whirling operation.

Fig. 5 is a side view of the lumber holding yoke-cams operating mechanism to show its attachment on the frame.

Fig. 6 is a perspective view of a section of a load of lumber to show my method of piling it and my method of forcing the air through the piled lumber.

Fig. 7 is an end view of the smaller air scoops that help to force the air through the lumber air spaces.

Fig. 8 is a sectional plan view on line 8—8 of Fig. 7, and

Fig. 9 is a sectional view of the cage revolving means.

The apparatus proper consists of an open ended two cage structure 1, built of structural steel in accordance with the well-known methods prevailing in this art, said cages being opposingly mounted and balanced relative to one another on a platform 2, through the center of which dual cage structure is mounted a central horizontal shaft 3, Figs. 1, 2 and 3, said horizontal shaft serving as a rotary support for said cage structure 1.

On platform 2, in each cage, are fastened two steel rails 4 forming a track in each cage of the same gauge as that of the car tracks 5 built over wooden trestles 6, in the drying room R, Fig. 1, over which the lumber trucks A' are conveyed from the sawmill to the cage structure and thence to the drying kiln, not shown.

Each cage is provided with an air scoop, or air directing hood, 7, of a width equal to the length of the cage. The object of these scoops, the construction of which needs no special description here, is to direct the air through the cages to discharge on the opposite sides, the air velocity and pressure (as it passes through the openings between the openly packed lumber, B', on the cars) being proportional to the revolving speed of the apparatus around its axle, in the direction of arrows 8, Fig. 3.

As it is necessary that the lumber on the

cars be securely held in place during the whirling to which it is subjected for its dehydration, I provide each cage with a compressing device constructed as set forth below.

Transversely across the top of each cage, on each of the two steel uprights 9, and extending upwardly and downwardly on each side of platform 2 on which they are securely riveted at 10, I fasten a pair of steel angles 11. Each pair of these angles 11 supports two lumber locking cams 12, which, by their rotation around pivots 13, raise or lower a clamping yoke 14, Figs. 3 and 4 lying directly across the top of the stacked lumber. When the cams 12 are turned downwardly, the yokes 14 press the lumber B' downward onto the platform C' of the car, the pressure being exerted throughout the whole mass through the trucks A' to the rails 4 and thence onto platform 2, and thus hold securely in position the truck and its load of lumber, with no possibility of the cars and lumber being accidentally released by the centrifugal force to which they are subjected.

It will be noted that the yokes 14 are available for clamping the mass of material in the cage against the centrifugal movement without the use of the cars or trucks, the rails 4 being omitted and the mass clamped down on the platform 2.

Each cam 12 is operated by means of an upwardly extending forked lever-arm 15, Figs. 3 and 4, linked to a steel bar 16 operated by a forked lever-arm 17 keyed to a common shaft 18.

Shaft 18 is operated by means of a double forked angle lever 19 connected by a threaded strain rod 20 to the compression mechanism, generally denoted by M, Figs. 3 and 4, of which each cage may have as many as it has pairs of uprights, but in my preferred construction as herein shown I may use only one pair for each cage.

Mechanism M is composed of a bracket 21 Figs. 4 and 5, a threaded ratchet 22, a take-up tension spring 23, a spring support nut washer 24 and a ratchet lever 25. Bracket 21, which is pivotally fastened on the central steel plate 26 by a pivot 26', guides rod 20 by means of two extending arms 27. The compression operation is obtained by means of the ratchet-lever 25 turning or screwing the ratchet upwards along the threaded rod 20 which, on account of the counter pressure of spring 23 against the nut washer 24 lying on the hub of the ratchet, is forced downwards and thus by means of lever 19, which is keyed on shaft 18, forces all cams 12 to press yokes 14 downwardly upon the lumber.

Another object of spring 23 is to give a certain elasticity to the clamping yokes 14 by making them take up the shrinkage in the lumber as it dries, and to keep the stackers

or lumber spacers 28 under constant compression in the lumber during speed and shrinkage variations, and to hold them rigidly under the forces generated by the braking of the apparatus to stop rotation.

Figs. 1 and 6 show how the lumber is piled upon the cars A'. All the boards are placed longitudinally on the car platform with the wooden stackers or spacers 28, of approximately not less than one inch thick for lumber, and not less than one-quarter inch for thin veneer. This leaves air spaces between the boards for the passage therethrough of air, but as the ends of the boards present a substantially flat surface, in the aggregate, when being rotated, their combined area forms practically a perfect wall against the air, and unless great revolving speed is given the apparatus, to increase the air velocity or pressure, very little air passes between the boards and the speed of the drying process is delayed. This phenomena is most noticeable when dehydrating square blocks of wood, and, owing to their aggregate surface mass, it becomes necessary to place them transversely across the cars with the air spacers 28 therebetween lying longitudinally.

In order to overcome the tendency to block the passage of air through an open lumber pile as described in the foregoing paragraph, and to individually direct the air pressure through the open air spaces shown in the lumber pile B', I have provided the form of V-shaped metal deflector 29, Figs. 7 and 8, which is suitably affixed to the edges of the front exposed ends of the boards to be acted on upon the air inlet or pressure side of the pile B', whereby the tendency of the air to slip by the face of the pile is obviated and the air is compelled by these deflectors to pass through the interstices or spaces between the said boards at high speed and under great pressure, the air emitting from the exhaust side as at W, Fig. 2, after passing entirely through the open pile B'. This action subjects the major portion of the surface of the wet lumber to the absorption action of the air, with the result that the large volumes of air passing through the lumber pile take up and rapidly carry away large quantities of moisture.

The centrifugal action of the high rotation of the lumber tends to forcibly throw the internal moisture content of the lumber to the surfaces, thereby to expose it to the absorption action of the air.

The velocity of the air through the open spaces of the piles of lumber is dependent on the revolving speed of the cages. The maximum peripheral lineal speed, I have ascertained as necessary, is of about 3600 ft. per minute, the minimum being not less than 2500 ft. p. m., the variation in speed depending on the kind of lumber to be

dried. To impart such variable, rotative speed to my apparatus I have found that the best method is shown at Fig. 9, wherein a screw worm 30 and a work-wheel 31 are utilized to give the necessary control. Worm 30 is keyed on shaft 32 supported by supports 33 transversely located beneath the worm wheel 30 on extension 34 of the supporting base B of my apparatus. A pulley 35 keyed to shaft 32 may be driven by an overhead shaft and pulley 36, Fig. 1, or directly by an electric motor, not shown.

Worm wheel 30 is loose on end of shaft 3 and engages a driving spring-ratchet dog 37 keyed on shaft 3. This construction permits me to shut off the power derived from pulley 36 whenever I so desire, to free the worm and worm wheel and the apparatus may freely rotate until the acquired momentum is exhausted, or it may be more rapidly stopped by the application of a brake 38 located on the opposite end of shaft 3 on extension 39 of base D' of the apparatus.

In Fig. 1 in which is shown a longitudinal front elevation, of my apparatus in operative form, a trestle or framing, generally denoted by 6, supports an interrupted rail structure 5 in the center of which is mounted my rotary apparatus, generally denoted by 1, said apparatus being so mounted that the loaded trucks may be pushed upon the rails 4 which are carried on the oppositely mounted cages.

In loading the trucks one of the cages is brought to register with the tracks 5 and a loaded truck is pushed thereon, the cage in the meanwhile being brought in through the closable opening PE and held by any suitable locking means, not shown. After the truck has been brought in through the closable opening PE and positioned in the cage, the operator, who stands upon the platform C, Fig. 3, operates ratchet 22 by means of lever 25 to close the lumber compressing yokes 14 sufficiently to permit the truck of the upper cage to be locked in operative position. The previously mentioned cage locking means is then released and the truck and overloaded cage is permitted to roll over, thereby bringing the lower empty half of the cage into operative relation with the tracks 5, and the second truck is pushed thereon and locked as previously described.

After dehydration has taken place the trucks are pushed from the cage and are passed out of the dehydrating room, in the direction of the arrow 40, through the opening P' of the room R, said opening being controlled by any suitable closure means, such as E'.

Having thus described my invention, I claim:

1. Apparatus for dehydrating lumber comprising cages supported for rotation

with a common shaft; means for rotating said shaft; and clutch means normally cooperating between said means for rotating and said shaft for rotating the shaft and upon stopping of the means for rotating 79 permitting continued rotation by momentum of the shaft and the cages rotating therewith.

2. Apparatus for dehydrating lumber comprising cages supported for rotation with a common shaft; means for rotating said shaft; clutch means normally cooperating between said means for rotating and said shaft for rotating the shaft and for releasing the shaft from the means for rotating 80 for permitting continued rotation of the shaft and the cages by momentum; and brake means for stopping continued rotation of said shaft and cages.

3. Apparatus for dehydrating lumber comprising cages supported for rotation with a common shaft; means for rotating said shaft; clutch means normally cooperating between said means for rotating and said shaft for rotating the shaft and for releasing the shaft from the means for permitting continued rotation of the shaft and the cages by momentum; and band brake means for stopping continued rotation of 95 said shaft and cages.

4. Apparatus for dehydrating lumber comprising cages supported for rotation with a common shaft; means for rotating said shaft; lumber piled in the cages in super-imposed portions spaced apart for 100 providing air spaces between the superimposed portions; and substantially V-shaped deflectors attached to the edges of the superimposed portions on the forward rotating 105 side of the portions.

5. Apparatus for dehydrating lumber comprising cages supported for rotation with a common axis; means for rotating said shaft; lumber piled in the cages in superimposed portions spaced apart for 110 providing spaces between the superimposed portions; air scoops on the cages; and V-shaped deflectors positioned between the various layers in the lumber pile for cooperating with the air scoops for positively directing air through said spaces during rotation 115 of the cages.

6. Apparatus for dehydrating lumber comprising cages supported for rotation with a common shaft; means for rotating 120 said shaft; lumber piled in the cages in superimposed portions spaced apart for providing spaces between the superimposed portions; air scoops on the cages; and substantially V-shaped deflectors attached to the edges of the superimposed portions on the forward rotating side of the portions.

7. Apparatus for dehydrating lumber comprising cages supported for rotation with a common shaft; means for rotating said 130

shaft; means for permitting continued rotation of the cages after said means for rotating is stopped; lumber piled in the cages in superimposed portions spaced apart for providing spaces between the superimposed portions; means for preventing rotation of the cages while the lumber is being piled therein; means for securing the lumber in the cages against centrifugal movement during rotation; air scoops on the cages; and means for positively directing air through said spaces from the front to the rear thereof while the cages are rotated.

8. Apparatus for dehydrating lumber comprising cages supported for rotation with a common shaft; means for rotating said shaft; means for permitting continued rotation of the cages after said means for rotating is stopped; means for stopping said continued rotation of the cages; lumber piled in the cages in superimposed portions spaced apart for providing spaces between the superimposed portions; means for preventing rotation of the cages while the lumber is being piled therein; clamping means for securing the lumber in the cages against centrifugal movement during rotation; air scoops on the cages; and substantially V-shaped deflectors attached to the edges of the superimposed portions on the forward rotating side of the portions.

9. Apparatus for dehydrating lumber comprising cages supported for rotation with a horizontal shaft; means for rotating the shaft; tracks in the cages; trucks received in the cages and positioned on said tracks for rotation with the cages; and means for releasing the shaft from said means for rotating and for permitting continued rotation of the cages by momentum after the shaft is so released.

10. Apparatus for dehydrating lumber comprising cages supported for rotation with a horizontal shaft; means for rotating the shaft; tracks in the cages; trucks received in the cages and positioned on said tracks for rotation with the cages; means for releasing the shaft and for permitting continued rotation of the cages by momentum after the shaft is so released; and means for stopping said continued rotation of the cages.

11. Apparatus for dehydrating lumber comprising cages supported for rotation with a horizontal shaft; means for rotating the shaft; tracks in the cages; trucks received in the cages and positioned on said tracks for rotation with the cages; means for preventing rotation of the cages during movement of the trucks to position on said tracks; means for releasing the shaft from said means for rotating and for permitting continued rotation of the cages by momentum

after the shaft is so released; and brake means for stopping said continued rotation of the cages.

12. Apparatus for dehydrating lumber comprising cages supported for rotation with a horizontal shaft; tracks in the cages; trucks received in the cages and positioned on said tracks for rotation with the cages; lumber piled on the trucks in superimposed portions arranged transversely of the cages and spaced apart by spacers arranged longitudinally of the cages for providing spaces between the superimposed portions; means for rotating said shaft; and cam-shaped clamping means for securing the trucks and superimposed portions in the cages for preventing centrifugal movement of the trucks and superimposed portions during rotation of the cages.

13. Apparatus for dehydrating lumber comprising cages supported for rotation with a horizontal shaft; tracks in the cages; trucks received in the cages and positioned on said tracks for rotation with the cages; lumber piled on the trucks in superimposed portions arranged transversely of the cages and spaced apart by spacers arranged longitudinally of the cages for providing spaces between the superimposed portions; means for rotating said shaft; a plurality of gripping cams operable from a single lever for securing each of the trucks and superimposed portions in the cages for preventing centrifugal movement of the trucks and superimposed portions during rotation of the cages; and means for positively directing air through said spaces from the front to the rear thereof while the cages are rotated.

14. Apparatus for dehydrating lumber comprising cages supported for rotation with a horizontal shaft; tracks in the cages; trucks received in the cages and positioned on said tracks for rotation with the cages; lumber piled on the trucks in superimposed portions arranged transversely of the cages and spaced apart by spacers arranged longitudinally of the cages for providing spaces between the superimposed portions; means for rotating said shaft; means for preventing rotation of the cages while the trucks are moved to position therein; a plurality of cam gripping cams for securing the trucks and superimposed portions in the cages for preventing centrifugal movement of the trucks and superimposed portions during rotation of the cages, toggle links connecting said cams and operable by a single lever; air scoops on the cages; and means for positively directing air through said spaces of the superimposed portions from the front to the rear thereof while the cages are rotated.

JAMES A. CRAIG,
